UNITED STATES PATENT OFFICE.

WALTER M. CROSS, OF KANSAS CITY, MISSOURI. ASSIGNOR TO GASOLINE PRODUCTS COMPANY, OF NEW YORK, N. Y., A CORPORATION OF NEW YORK.

DEPHLEGMATOR.

Application filed October 31, 1923. Serial No. 672,021.

This invention relates to a dephlegmator which is so constructed that the hydro-carbon vapors of a high boiling point will be separated by condensation from those of a lower boiling point and the liquid entrained with the latter vapors will be separated therefrom and together with the condensate will be reboiled, causing a further separation.

10 The invention further contemplates the utilization of the charging stock as a cooling medium in the dephlegmator to separate by condensation the vapors of a high boiling point from those of a lower boiling point 15 by condensing the former and the absorption of the heat from the vapors by the charging stock to preheat the latter before it enters the still for final heating.

In the drawing I have illustrated a vertical sectional view of a dephlegmator constructed in accordance with my invention.

This embodiment of the invention includes an outer shell 1, which may be of any desired form but which is preferably cylindrical, 25 having a vapor inlet 2 at the bottom and a vapor outlet 3 at the top thereof. Suspended within this outer shell 1 is a container 4 which is preferably of similar cross-section to that of the outer shell 1 but of less 30 diameter so that a space 5 is left between the container 4 and the shell 1. This container is provided with closed side walls, a closed bottom and an open top 6, and is supported by suitable means such as brackets 7 35 in the shell 1 in spaced relation to the bottom of the latter, and is of such length that it terminates short of the top of the shell.

A pipe 8 leading from a hydro-carbon oil supply extends through the shell 1 and 40 circles the container 4. The end 9 of this pipe is connected to the still in which the temperature of the oil is raised to a point of vaporization. It will be seen that in the form of the invention illustrated in the 45 drawing the pipe is arranged in convolutions which are of helical form and these convolutions are located in the space 5 between the shell 1 and the container 4. A helical baffle 10 is likewise arranged within 50 this space and overlies the convolutions of the pipe 8 so as to cause the vapors, which pass upwardly from the lower end of the shell 1, to follow a convolute path around the coils of the pipe 8 and around the container 4.

At the lower end of this shell 1 a vapor space 11 is provided by a partition 12 and this vapor space communicates with the remainder of the interior of the shell 1 through a plurality of pipes 13 which have on their upper ends, elbows 14. These elbows permit the passage of the vapors into the interior of the shell 1 but prevent any return of liquids through the pipes into the vapor space 11. The lower end of the shell 1 is 60 provided with an outflow pipe 15 which, when the liquid in the lower end of the shell reaches a predetermined point, is opened by an automatically operable valve 16 to permit an outflow of the liquid until the predetermined normal level is reached.

The outlet pipe 3 at the upper end of the tower is connected to a plurality of purifiers or separators 17 which function to separate the entrained liquid globules from the outflowing vapor. The detail of the construction of the purifier or separators is the same as a separator used in steam boiler practices consisting of a plurality of obstructing or baffling elements which serve to retard the flow of the vapors to the extent that the entrained liquid material therein is separated out. Each of these separators is provided with a return pipe 18 having a discharge 80 nozzle 19 on its lower end. These return pipes extend into the container 4 with the nozzle adjacent to the lower end thereof so that the separated liquid is returned to the lower portion of the tower and discharged into the container 4 for further vaporization.

Connecting this container 4 with the lower end of the shell 1 is an overflow pipe 20 which conducts the accumulated liquid from the container 4 into the lower end of the shell 1 when the liquid in the container reaches a predetermined level.

It will be seen that when the vapors enter the shell 1 through the inlet pipe 2 they pass from the vapor space 11 upwardly through the pipes 13 and are discharged into the tower or shell proper 1. Thus discharged, the vapors pass upwardly through the space 5 around the container 4 following a convolute path between the coils of the pipe 8. The vapors of the higher boiling point are condensed upon contact with this pipe and fall back into the lower end of the tower where they accumulate around the pipes 13. The vapor of the lower boiling point passes into the upper end of the 110

tower and thence through the separators 17 and out through the outlet 3 for further treatment. The liquid separated from the vapors by the separator 17 is returned 5 to the container 4 where it is re-heated by the inflowing vapors which pass upwardly of the tower and thus subjected to a second vaporization so that the vapors of the lower boiling point are again separated 10 from those of the higher boiling point, those of the higher boiling point overflowing into the pipe 20 and back to the lower end of the tower where a further reboiling and vaporization takes place. Of course, the continuous 15 passage of the hot vapors through the pipes 13 heats the accumulated liquid in the lower end of the tower so that reboiling and consequent vaporization continues until there remains gas-oil which is drawn off through 20 the pipe 15 as hereinbefore described.

It is, of course, understood that the contact of the rising vapors with the pipe 8 results in a heat exchange which not only condenses the vapors but pre-heats the oil in the 25 pipe 8 before it reaches the still.

While I have illustrated and described a particular embodiment of my invention it

has merely been for the sake of convenience of disclosure but I do not wish to be limited to that particular embodiment as it is obvious that many changes may be made in the details of construction without departing from the spirit of the invention, or exceeding the scope of the claim.

I claim:

A dephlegmating means, comprising a shell having vapor inlet and outlet ports, a partition in the lower portion of the shell, a plurality of vertical vapor inlet pipes extending through the partition, an open top 40 container of less diameter than the shell supported therein and forming an annular space for passage of the vapors from the bottom to the top of the shell, means positioned in the top of the shell for separating 45 and returning the liquid material mechanically entrained in the vapors to the inner container, a coil in the annular vapor space for refluxing the heavier fractions from the vapors to a pool supported by the lower partition wherein the liquid condensate is subjected to reheating by the heat of the incoming vapors.

WALTER M. CROSS.
